(57) **CLAIM**

The ornamental design for a fitting hinge, as shown and described.

DESCRIPTION

FIG. 1 is a front view of a fitting hinge embodying my new design;

FIG. 2 is a rear view thereof;

FIG. 3 is a top plan view thereof;

FIG. 4 is a bottom view thereof;

FIG. 5 is a right side view thereof;

FIG. 6 is a left side view thereof;

FIG. 7 is a front view at time of closing state thereof;

FIG. 8 is a rear view at time of closing state thereof;

FIG. 9 is a cross sectional view taken along line 9—9 of FIG. 1.

FIG. 10 is a sectional view along line 10—10 thereof;

FIG. 11 is a sectional view along line 11—11 thereof;

FIG. 12 is a sectional view along line 12—12 thereof;

FIG. 13 is a sectional view along line 13—13 thereof;

FIG. 14 is a sectional view along line 14—14 thereof;

FIG. 15 is a sectional view along line 15—15 thereof;

FIG. 16 is a perspective view seen from front position thereof;

FIG. 17 is a perspective view seen from rear position thereof;

FIG. 18 is a perspective view at time of closing state seen from front position thereof; and,

FIG. 19 is a perspective view at time of closing state seen from rear position thereof.
